PRINTING MECHANISM

Frederick A. Beach, Metuchen, N. J., assignor to
Joseph Rubenstein, Brooklyn, N. Y.

Application March 13, 1933, Serial No. 660,509

12 Claims. (Cl. 101—336)

The present invention relates to improvements in printing mechanisms, particularly in those of the multigraphing type.

The general practice in printing with duplicating machines is to impart impressions of the characters or type carried by the printing cylinder of the machine to the paper to be printed, through a transfer ink ribbon mounted over the characters or type of the cylinder. It is, of course, apparent that after such machines have been in operation for a certain length of time, the ink initially contained in the ribbon becomes used up so that to continue the operation of the machine it is necessary to replenish the ink content of the ribbon.

Attempts have been made to do this without removing the ribbon from the machine by providing the machine with a reinking device comprising an ink fountain and rolls arranged to transfer the ink from the fountain to the ribbon while the machine is in operation. This device, however, has not been commercially successful. This is due for the most part to the fact that the character of the ribbons used is such as to preclude a uniform transmission of the applied ink to all parts of the ribbon. As a consequence, those parts of the ribbon contacting the transfer roller of the reinking device become supersaturated with ink and when the type is impressed on the paper through these portions of the ribbon, the surplus ink causes runs between the type producing smears and smudgy prints on the paper.

Workers in this art, therefore, in order to secure satisfactory prints have been forced, when the ribbons became depleted in ink, to remove the ribbons from the machines and replace them with new ribbons properly saturated with ink. This procedure is very similar to that employed to replace worn out ribbons in typewriters. Needless to say, this procedure besides being expensive is rather annoying and consequently objectionable from a commercial standpoint.

The present invention contemplates an improvement for overcoming the above objections comprising a wiping attachment for the transfer ribbon which permits reinking of the ribbon during operation of the machine by ensuring a removal of surplus ink and a uniform distribution of the ink throughout the ribbon.

It is accordingly an object of this invention to provide a process for effecting a uniform distribution of ink in a transfer ribbon of a printing mechanism during the reinking thereof.

It is a further object of this invention to provide a wiping attachment for the transfer ribbon of a duplicating machine having absorbent means

for removing surplus ink supplied during reinking of the ribbon.

Reference is now made to the accompanying drawings of which

Fig. 1 is a perspective view of a multigraphing machine in which my improvements are embodied.

Fig. 2 is a plan view of the ribbon wiper.

Fig. 3 is a section on line 3—3 of Fig. 2.

Fig. 4 is a diagrammatic view of a conventional ribbon inking device.

On the drawings:

The printing device disclosed in toto in Fig. 1 comprises a paper feeding section 1 and a printing section 2 mounted respectively on the supporting frames 3 and 3a which are secured together by fastening devices (not shown).

The printing mechanism 4a of the printing section is of conventional structure including as it does the usual printing cylinder 4, cylinder supports 5 providing the journals 5a, transfer ribbon 6 and platen (not shown). The cylinder is rotated by a motor 7 through suitable driving connections although rotation may be effected by the handle 7a if desired. Ink is supplied to the transfer ribbon through an inking attachment 8 of ordinary construction (Fig. 4) composed of an ink fountain 8a, transfer rolls 11 and intermediate rolls 9 and 10 operable in the manner shown in said figure. It will be appreciated that these printing parts are embodied in the general run of duplicating machines and constitute no part of this invention.

The ink supplied to the ribbon 6 by the transfer rolls 11 is distributed through the ribbon and excess ink removed from the ribbon by means of the ribbon wiper 12 shown in detail in Figs. 2 and 3. Said wiper 12 as will be perceived from Fig. 1, is secured to a rearwardly extending projection 14 of the supports 5 in a position to contact the ribbon 6 directly after the ribbon has had wiping contact with the transfer rolls 11.

The wiper 12 comprises a flat base 15 of wood or the like possessing narrow lateral extensions 16. The base 15 is secured in a metal pan 17 having a flat bottom 18, and vertical front and rear portions 19 and 20 of about the same height as the thickness of the base. Vertical wings 21 are formed on the lateral edges of the pan in front of the extensions 16 of the base 15. The pan also has lateral extensions 22, underlying and secured to the extensions 16 of the base 15. The rear edges 23 of said extensions are upturned along the rear of said extensions 16. Hinge sections 24 comprising pintle bearings 24a and hinge plates 24b are provided for securing said wiper to

the printing mechanism. It will be observed from a reference to Fig. 3 that said plates 24b extend below the level of the bottom of the wiper. Each of said hinge sections 24 is joined by a 5 pindle 25 with a hinge section 26 rigidly secured as by screws 27 to the upper face of a base extension 16.

A thick padding 28 of absorbent material such as felt or the like is disposed across the bottom 10 of the metal pan 17 with one end 17a overlying a portion of the upper face of the base 15. Stretched over the padding 28 is a further layer 29 of absorbent material such as felt, one end 30 of which is secured between portion 19 of the 15 metal pan and the front face of said base 15. The other end 31 is fastened to the upper face of the wooden base by brads 31a or the like which also penetrate the underlying portion of the padding.

20 The wings of the metal pan provide journals for a pair of spaced shafts 33 and 34, one end of which is provided with headed members 35, such as wing nuts, rigid therewith. The other end of the shafts is reduced in size and threaded for the 25 reception of removable wing nuts 36, which can be turned up on the shafts to lock the same in place.

The absorbent layer 29 is covered by a protecting strip of muslin or the like 37 the ends of 30 which are securely fastened to shafts 33 and 34. Said strip has a width substantially equal to that of the layer 29 but has a relatively great length. As will be noted, said strip passes from shaft 33, about the layer 29 and thence to shaft 34. The 35 movement of the strip is caused by turning the shafts 33 and 34, after release of nuts 36, which effects unreeling of the muslin from one shaft and a reeling up of the muslin on the other shaft.

The wiper when in use is attached to the projection 14 of the supports 5 at a point slightly above and to the rear of the central axis of the printing cylinder by means of a rigid connection 13 between the hinge plates 24b and said projection. Due to the location of the hinge pindle 45 25 with respect to the point of connection 13 it will be apparent that the wiper will tilt forward under the urge of gravity and rest against the surface of the printing cylinder. In order to properly adjust the pressure of the wiper against 50 the cylinder, one extension of the base 15 is provided with a headed set screw 38 the lower end of which is adapted to bear against the top of the supports 5. Rotation of the screw causes a 55 lowering or raising of the wiper as the case may be and consequently a change in the force with which the wiper acts on the printing cylinder.

The operation of the wiper is apparent from the foregoing structure. Ink is continuously supplied to the ribbon 6 by the reinking arrangement 8 which applies the ink to the ribbon at spaced points below the wiper. Rotation of the cylinder causes the reinked portions of the ribbon to pass beneath the absorbent surface of the wiper which acting directly against the ribbon 65 absorbs surplus ink and effects a distribution of the ink through the ribbon. In this way the printing is always effected upon a properly inked ribbon and consequently the prints obtained are always clear and distinct. Whenever the muslin 70 surface arranged over the bottom of the wiper becomes worn, a fresh surface is provided, by rotating the shafts 33 and 34 as before explained.

I claim:—

75 1. The process for reinking the transfer ribbon of a duplicating machine in which the ribbon

is carried by a rotatable printing roll, which comprises applying ink to the ribbon at one point in the rotation of the roll and removing surplus ink from said ribbon at another point in the rotation of said roll prior to the printing step. 5

2. The process for reinking a transfer ribbon of a printing machine while the machine is in operation which comprises applying ink to one surface of the ribbon and wiping surplus ink from said surface prior to the printing step at a point spaced from the point of application of the ink. 10

3. The process for reinking a transfer ribbon of a printing machine while the machine is in operation, which comprises applying ink to the ribbon and wiping the ribbon and absorbing surplus ink therefrom prior to the printing step at a point spaced from the point of application of the ink. 15

4. In combination with the transfer ribbon of a duplicating machine, means for applying ink 20 to one surface of the ribbon while the machine is in operation, and means adapted to bear against this surface of the ribbon at a point removed from the point of application of the ink to remove surplus ink from the ribbon. 25

5. The process for reinking a transfer ribbon of a printing machine while the machine is in operation, which comprises applying ink to one surface of the ribbon and removing surplus ink from said surface prior to the printing step by 30 subjecting the entire width of said surface to a simultaneous wiping and ink absorbing treatment at a point spaced from the point of application of the ink.

6. In combination with the transfer ribbon of a duplicating machine, means for applying ink 35 to the ribbon while the machine is in operation, and means comprising a wiper having a flat base covered by ink absorbent material adapted to bear against the ribbon at a point removed from the point of application of the ink to remove surplus ink from the ribbon. 40

7. The process for reinking a transfer ribbon of a duplicating machine while the machine is in operation, which comprises applying ink to one surface of the ribbon and removing surplus ink from said surface prior to the printing step by subjecting said surface to a simultaneous wiping and ink absorbing treatment, and varying the rigor of the wiping treatment during the operation of the machine. 45

8. In combination with the transfer ribbon of a duplicating machine, means for applying ink 50 to the ribbon while the machine is in operation and a wiper adapted to bear against the ribbon at a point removed from the point of application of the ink to remove surplus ink from the ribbon, said wiper comprising a base having a flat bottom, absorbent material secured over said bottom and means for protecting said absorbent material from the friction set up during wiping. 55

9. A device as defined in claim 8 wherein said wiper includes means for varying the pressure of the wiper on said transfer ribbon. 60

10. In combination with the transfer ribbon of a duplicating machine, means for applying ink to the ribbon while the machine is in operation and a wiper adapted to bear against the ribbon at a point removed from the point of application of the ink to remove surplus ink from the ribbon, said wiper comprising a base having a flat bottom, absorbent material secured over said bottom and a fibrous strip movable over said absorbent material for protecting said material from the friction set up during wiping. 65

11. In combination with the transfer ribbon of a duplicating machine, means for applying ink to the ribbon while the machine is in operation and a wiper adapted to bear against the ribbon at a point removed from the point of application of the ink to remove surplus ink from the ribbon, said wiper comprising a base having a flat bottom, absorbent material secured over said bottom, a pair of shafts journaled to said base, a strip of fibrous material having its ends secured to said shafts and trained about said absorbent material, and means for rotating said shafts to move said fibrous material.
12. A wiping attachment for removing surplus ink from the transfer ribbon of a duplicating machine, comprising a wooden base having a
- flat bottom, a metal pan disposed over and secured to said base, said pan having upturned sides providing supporting wings, a pair of shafts journaled in said wings, layers of absorbent material secured over the bottom of said metal pan, a strip of fibrous material having its opposite ends secured to said shafts and trained about said absorbent material, means for locking said shafts against rotation, means for rotating said shafts to cause different portions of said fibrous material to overlie said absorbent material and means for securing said attachment to the duplicating machine so as to bear against the transfer ribbon thereof.
